STORM DOOR CHECK

Filed Nov. 29, 1946

Inventor
Charles E. Gibbs

By Cushman, Darby & Cushman, Inc.
Attorneys

3. A door check assembly for a door frame, said assembly comprising a piston cylinder having open and choked vents fixed to the door frame and having a piston and a piston rod, a bracket in which is mounted a rotatable shaft carrying a spring-actuated bell crank lever assembly, one arm of which lever engages the door and the other arm of which engages the piston rod, the bracket and cylinder are adjustable relative to each other, so as to vary the leverage of the bell crank lever as may be desired, the piston rod extends completely through the cylinder so as to ensure correct piston play and proper movement of the bell crank lever, and eliminate any tendency of the piston to jam in its reciprocations in the cylinder and interfere with the proper operation of the check.

The present invention has to do with door checks. It is particularly designed for outer or storm door checks, but it will be understood that it may be used with any type of door which it is desired to check in its closing movements and avoid objectionable slamming.

Stated generally, the check comprises a piston cylinder having open and choked vents fixed to the door frame and having a piston and a piston rod. Secured to one end of the cylinder is a bracket in which is mounted a rotatable shaft carrying a spring-actuated bell crank lever assembly, one arm of which lever engages the door and the other arm of which engages the piston rod. The bracket and cylinder are adjustable relative to each other, so as to vary the leverage of the bell crank lever as may be desired. The piston rod extends completely through the cylinder so as to ensure correct piston play and proper movement of the bell crank lever, and eliminate any tendency of the piston to jam in its reciprocations in the cylinder and interfere with the proper operation of the check.

In the drawings herewith is illustrated one physical embodiment of the invention, and in said drawings:

Figure 1 is a view in elevation of the upper portion of a door and door frame with the check in position, the door being in closed position.

Figure 2 is a view in top plan of the check on substantially the line 2—2 of Figure 1, looking in the direction of the arrows, the door being shown in partially open position in dotted lines.

Figure 3 is a longitudinal sectional view on substantially the line 3—3 of Figure 1, looking in the direction of the arrows, to show the bracket, bell crank, piston, and piston rod.

Figure 4 is a cross-sectional view on substantially the line 4—4, Figure 1, looking in the direction of the arrows.

Figure 5 is a detail view of the supporting bracket.

Figure 6 is a detail view of the bell crank lever shaft.

Referring to the drawings by numbers, the same numbers designating the same parts in the several views, a substantially U-shaped bracket 10 is provided, which bracket is adjustably mounted on a piston cylinder, as presently described. Mounted in slots 13 in the side wings of bracket 10 is a shaft having cylindrical portions 14 to permit it to rotate in the bracket. Said shaft is of non-cylindrical formation on either side of the cylindrical portions 14, shown here as squared portions 15, which prevents

the shaft from being rotated in the slots 13. A piston 24 is mounted on the door frame 25 by a support 26, and in said cylinder 24 is a piston 27 of any suitable type, said piston 27 being secured to piston rod 22 which extends through the ends of cylinder 24 and by reason of its bearings in the cylinder ends, ensures smooth travel of the piston and prevents any jamming of the moving parts. The inner end of cylinder 24 engages lugs 28 on the end wall of bracket 10 for purposes of relative adjustment of bracket and piston. The parts are held in any adjusted positions by a sleeved nut 29 threaded in an opening in the end of cylinder 24. By shifting the position of the bracket 10 relative to the cylinder 24 the relation of the compression lever 17 to its contact surface 22 may be varied and the effective leverage of lever 17 altered to meet varying conditions, such as occur with doors of different weights or to increase or decrease rapidity of closing action.

At its inner end cylinder 24 is provided with an open vent 30, which permits piston 27 to move freely and without checking when the door is opened and the tensioning spring 18 moves the bell crank levers, piston rod, and piston toward the inner end of the cylinder. At its outer end the cylinder 24 has a choked vent 31, of any suitable adjustable type, so that movement of piston 27 toward the outer end of the cylinder 24 under the impact of the closing door will be re-

UNITED STATES PATENT OFFICE

2,446,004

STORM DOOR CHECK

Charles E. Gibbs, Middletown, Ohio

Application November 29, 1946, Serial No. 712,985

4 Claims. (Cl. 16—84)

1

shifting of the shaft longitudinally in bracket 10.

One end of the squared portion 15 of the shaft extends a considerable distance beyond the side wing of bracket 10 and receives the door contact lever 16 of the bell crank lever, which has a square opening to engage the squared end 15 of the shaft, so as to turn therewith. A tensioning spring 18 is provided with one end anchored to bracket 10 and the other end engaging lever 16 to hold the bell crank always in operative relation to the door 12, a contact plate 19 being provided against which the door contact lever 16 bears.

Compression lever 17 is mounted on the squared central portion 15 of the shaft so as to turn therewith and projects through a fork 20 secured to the end of piston rod 21. Said fork 20 has a curved end wall 22 against which lever arm 17 rides, ensuring smooth travel of the parts. At its outer end the fork 20 has a stop pin 23 which prevents arm 17 from escaping from the fork.

With this bell crank lever assembly it will be seen that the lever arms 16 and 17, tensioned by spring 18, will be held always in proper relation to the door and piston fork to respond to movements of the door.

Piston cylinder 24 is mounted on the door frame 25 by a support 26, and in said cylinder 24 is a piston 27 of any suitable type, said piston 27 being secured to piston rod 22 which extends through the ends of cylinder 24 and by reason of its bearings in the cylinder ends, ensures smooth travel of the piston and prevents any jamming of the moving parts. The inner end of cylinder 24 engages lugs 28 on the end wall of bracket 10 for purposes of relative adjustment of bracket and piston. The parts are held in any adjusted positions by a sleeved nut 29 threaded in an opening in the end of cylinder 24. By shifting the position of the bracket 10 relative to the cylinder 24 the relation of the compression lever 17 to its contact surface 22 may be varied and the effective leverage of lever 17 altered to meet varying conditions, such as occur with doors of different weights or to increase or decrease rapidity of closing action.

At its inner end cylinder 24 is provided with an open vent 30, which permits piston 27 to move freely and without checking when the door is opened and the tensioning spring 18 moves the bell crank levers, piston rod, and piston toward the inner end of the cylinder. At its outer end the cylinder 24 has a choked vent 31, of any suitable adjustable type, so that movement of piston 27 toward the outer end of the cylinder 24 under the impact of the closing door will be re-

tarded and slamming of the door, whether it is manually or spring closed, will be prevented.

In operation the opening of the door will permit the bell crank lever, the piston rod, and piston, to move freely to checking position under the action of the tensioning spring. This will set the door contact lever in substantially the position shown in dotted lines in Fig. 2, ready to receive the impact of the closing door. When the door closes it will strike the contact lever which, through compression lever, piston rod, and choked piston, will be retarded, slow down movement of the door, and prevent slamming. This checking action will be supplemented to some extent by the tensioning spring which moves the bell crank lever to their outer door-checking position, but resists their return.

From the disclosure here made it will be seen that an effective door check is provided and one in which the parts may be readily made and assembled; that the construction permits adjustment to meet varying needs; and when once assembled, danger of derangement of the parts in use is minimized.

Such changes from the specific disclosure herein as amount only to mechanical skill and fall within the terms of the appended claims are to be regarded as within the range of the invention.

I claim:

1. A door check comprising a piston cylinder fixed to the door frame and having an open vent at one end and a choked vent at the other end, a bracket having side wings secured to one end of said cylinder, a shaft rotatably mounted in the side wings of said bracket, a door contact lever mounted on said shaft, a compression lever mounted on said shaft between the bracket wings in spaced relation to said contact lever, a tensioning spring tending to move said levers to

door checking positions, a piston rod carrying a piston traversing said cylinder and engaging said compression lever, and a threaded sleeve on said rod adjustably to connect said bracket and said cylinder.

5 2. A door check comprising a piston cylinder fixed to the door frame and having an open vent at one end and a choked vent at the other end, a bracket having side wings secured to one end of said cylinder, a shaft rotatably mounted in the side wings of said bracket, a door contact lever mounted on said shaft, a compression lever mounted on said shaft between the bracket wings in spaced relation to said contact lever, a tensioning spring tending to move said levers to 10 door checking positions, a piston rod carrying a piston traversing said cylinder and engaging said compression lever, lugs on said bracket abutting the end of said cylinder, and a threaded sleeve on said rod adjustably to connect said bracket lugs and said cylinder.

15 3. The invention as defined in claim 1 in which the side wings of the bracket are slotted to receive the rotatable shaft.

20 4. The invention as defined in claim 2 in which the cylinder abutting lugs project inwardly from the bracket wings in spaced apart relation.

CHARLES E. GIBBS.
